UNITED STATES PATENT OFFICE

148,217

DESIGN FOR A SHIRT

Abraham Dunner, New York, N. Y.

Application September 20, 1945, Serial No. 122,195

Term of patent 14 years

(Cl. D3—25)

To all whom it may concern:

Be it known that I, Abraham Dunner, a citizen of the United States, residing in New York city, county of New York, and State of New York, have invented a new, original, and ornamental Design for a Shirt, of which the following is a specification, reference being had to the accompanying drawing, forming part thereof.

In the drawing:

I claim:

The ornamental design for a shirt, as shown.

ABRAHAM DUNNER.
